UNITED STATES PATENT OFFICE

FRANK J. MCGUINNESS, OF WEBSTER, MASSACHUSETTS

DOORLATCH STRIKER

Application filed October 24, 1928. Serial No. 314,754.

This invention relates to locks and latches and more particularly to a striker adapted to be secured to a door jamb and engaged by the bolt or plunger of a door latch so that a door may be secured in a closed position.

One object of the invention is to provide a striker particularly adapted for use upon an automobile, although it is not restricted to this specific use and may be applied to any door jamb of such construction and dimensions that will accommodate the striker.

Another object of the invention is to provide a striker reduced in thickness toward its forward end to provide a sloping outer side face and at its forward end terminating in a feathered lip so that the plunger of a door latch may easily move onto the outer surface of the striker across which it passes into position to contact with the rear end face of the striker and securely retain a door closed.

Another object of the invention is to provide a striker including rotatably mounted members which project from the sloping outer side face of the striker and are adapted to be engaged by the plunger of a lock and facilitate movement of the plunger across the striker, thereby eliminating danger of the plunger failing to move entirely across the striker into position to firmly secure a door. By this arrangement there will be no danger of the door of an automobile not being properly secured and accidentally swinging open.

The invention is illustrated in the accompanying drawing, wherein

Figure 1 is a view showing a portion of a door and door jamb in transverse section and the improved striker in top plan with the plunger of a door latch in position to engage the striker and secure the door,

Fig. 2 is a view looking at the outer side face of the striker, and

Fig. 3 is a transverse sectional view through the striker taken on the line 3-3 of Fig. 2.

The improved striker consists of a body or block 1 formed of metal and this body which is rectangular in shape, as shown in Fig. 2, has its corner portions formed with openings 2 through which screws 3 are to be

passed to firmly secure the striker against the edge face of a door jamb 4, as shown in Fig. 1. The outer end portions of the openings 2 are flared to accommodate the heads of the screws and prevent the screws from projecting outwardly beyond the outer side face of the striker. A pocket 5 which opens through the outer side face of the body is formed in the striker and this pocket is of rectangle shape and so located that the screw-receiving openings are disposed between the pocket and the margins of the striker. Pins 6 extend transversely through the striker and these pins pass through the pocket transversely thereof in spaced relation to each other longitudinally of the striker. The pin which is adjacent the rear end of the pocket carries a roller 7 and each of the remaining pins carry anti-friction balls 8 which turn freely upon the pins and are retained in

spaced relation to the walls of the pocket by spacing washers or disks 9. The roller and the anti-friction balls 8 are of such size that, when mounted upon the pin 6 within the pocket 5, they project slightly beyond the outer side face of the body of the striker for engagement with the plunger 10 of a latch carried by a door 11. It should be noted that the body portion of the striker is reduced in thickness from its rear end towards its forward end and, therefore, the outer side face of the striker curves inwardly from its rear end towards its forward end and adjacent the forward end of the striker the outer side face projects forwardly at an inward incline

to form a lip 12 which is feathered, as clearly shown in Fig. 1. By having the striker formed in the manner described above and shown clearly in Fig. 1, the plunger of the door latch may very easily ride into engagement with the outer surface of the striker when the door is closed.

When the improved striker is in use, it is applied to the side edge face of the door jamb 4 and preferably secured in a pocket 13 formed therein and secured by the screws 3. The straight cut rear end of the striker terminates in spaced relation to the rear end of the pocket 13, thereby leaving ample room for the plunger 10. When the door is closed,

the plunger 10 will ride into the pocket 13 and the roller 7 will engage the outer side face of the striker, thereby firmly securing the door.

It is to be noted that the pocket 5 is formed in the side edge face of the striker and, therefore, the outer side face of the striker is reduced in thickness from its rear end towards its forward end and, therefore, the outer side face of the striker curves inwardly from its rear end towards its forward end and adjacent the forward end of the striker the outer side face projects forwardly at an inward incline

to form a lip 12 which is feathered, as clearly shown in Fig. 1. By having the striker formed in the manner described above and shown clearly in Fig. 1, the plunger of the door latch may very easily ride into engagement with the outer surface of the striker when the door is closed.

When the improved striker is in use, it is applied to the side edge face of the door jamb 4 and preferably secured in a pocket 13 formed therein and secured by the screws 3. The straight cut rear end of the striker terminates in spaced relation to the rear end of the pocket 13, thereby leaving ample room for the plunger 10. When the door is closed,

the plunger 10 will ride into the pocket 13 and the roller 7 will engage the outer side face of the striker, thereby firmly securing the door.

It is to be noted that the pocket 5 is formed in the side edge face of the striker and, therefore, the outer side face of the striker is reduced in thickness from its rear end towards its forward end and, therefore, the outer side face of the striker curves inwardly from its rear end towards its forward end and adjacent the forward end of the striker the outer side face projects forwardly at an inward incline

the plunger engages the lip 12 of the striker and as it moves along the outer surface of the striker the plunger will be forced towards a retracted position. It often happens that 5 frictional binding between the plunger and a striker will prevent the door of an automobile from closing tightly unless it is slammed shut, but in view of the fact that I have provided the balls 8 and roller 7 which rotate 10 when engaged by the plunger, frictional binding will be eliminated and the door may be easily closed. When the door is fully closed, the plunger will have passed the striker and will be projected into the rear end portion 15 of the pocket 13 where it will contact with the straight cut rear end face of the striker and very securely retain the door in a closed position. I have, therefore, provided a striker which will be very efficient in its operation 20 and of such construction and dimensions that it may be easily substituted in place of strikers already in use. Since the balls adjacent the outer end of the pocket are of less diameter than the intermediate balls, the 25 plunger will be permitted to easily ride from one set of balls to the other and since a roller is used at the inner end of the pocket the plunger will be engaged its full width and very easily moved to the position shown in 30 Fig. 1.

Having thus described the invention, I claim:

A striker comprising a block adapted to be secured against a door jamb and having 35 a flat inner end face and an outer side face extending from the end face, the block being reduced in thickness towards its other end to facilitate movement of a latch plunger along the block, said block having a pocket 40 opening through its outer side face and spaced from its inner end, pins extending transversely through said pocket in spaced relation to each other longitudinally thereof, a roller in the inner end portion of said pocket rotatably 45 mounted upon one pin, and a plurality of balls rotatably carried by each of the remaining pins between the roller and outer end of the pocket, the balls closest to the outer end 50 of the pocket being of reduced diameter and said roller and balls projecting out of the pocket an equal distance and adapted to engage a latch plunger and facilitate movement of the plunger along the block into position to engage the said inner end face of the block 55 in overlapping relation thereto and retain a door closed.

In testimony whereof I affix my signature.
FRANK J. McGUINNESS. [L. S.]
